CLAIM

The ornamental design for a pet toy, as shown and described.

DESCRIPTION

FIG. 1 is a perspective view of a pet toy of the present invention showing our new design;

FIG. 2 is a front elevational view thereof;

FIG. 3 is a top plan view of the pet toy of FIG. 1; and,
FIG. 4 is right side elevational view of the pet toy of FIG. 1.

The broken lines shown in the drawings depict portions of the pet toy that form no part of the claimed design.
